UNITED STATES PATENT OFFICE.

ALBERT R. THAYER, OF BOSTON, MASSACHUSETTS, ASSIGNOR TO F. H. ROBERTS COMPANY, OF BOSTON, MASSACHUSETTS, A CORPORATION OF MASSACHUSETTS.

DESIGN FOR A TOP FOR CANDY BOXES.

Application filed October 15, 1925. Serial No. 15,125. Term of patent 14 years.

To all whom it may concern:

Be it known that I, ALBERT R. THAYER, a citizen of the United States, residing at Boston, in the county of Suffolk and State of Massachusetts, have invented a new, original, and ornamental Design for Tops for Candy Boxes, of which the following is a specification, reference being had to the accompanying drawing, forming part thereof.

The figure shows in perspective a candy box fitted with a top showing my new design.

I claim:

The ornamental design for a top for candy boxes as shown.

ALBERT R. THAYER.
